UNITED STATES PATENT OFFICE.

OLE M. AARSETH, OF ECHO, MINNESOTA.

MAIL-BOX MOUNTING.

Application filed May 9, 1925. Serial No. 29,082.

This invention relates to pivotal mountings for mail boxes or other receiving and delivering apparatus. The ordinary rigidly mounted mail box is often struck down or bent out of shape by the mail carrier's vehicle or by passing vehicles or animals on the road. Oftentimes the mail carrier, in attempting to gauge the proper point at which to stop to deliver his mail, misjudges the distance and his vehicle skids in the ditch along the road, resulting in the outward end of the mail box being violently struck by the adjacent side of his vehicle.

It is the main object of this invention to provide an extremely but highly efficient pivotal mounting adapted to be attached to a standard mail box which will not only permit the box, if struck, to readily be swung without damage thereto but which will, moreover, automatically return the box to proper position on the post or other support.

It is a more specific object of the invention to provide a pivotal mounting for a mail box or other receptacle, comprising a pair of telescoped pivot members, one of which is attached to the post or support, the other of which is attached to the bottom of the mail box or other receptacle, said members having interposed therebetween an inclined bearing surface adapted to automatically swing the box back to normal position when, for any reason, it has been swung therefrom.

These and other objects of the invention will be apparent from the following description made in connection with the accompanying drawings, wherein like notations refer to similar parts throughout the several views, and in which,

Fig. 1 is a side elevation of a standard mail box with some parts shown in section, supported by means of the improved pivotal mounting from an ordinary post;

Fig. 2 is a side elevation on an enlarged scale of one of the pivot members detached, some parts being broken away;

Fig. 3 is a side elevation on an enlarged scale of the other pivot member attached; and

Fig. 4 is a bottom plan view on an enlarged scale of the socket carried by the box.

In the drawings, numeral 5 denotes a standard mail box supported from the usual post or upright standard 6. A socket plate 7, provided with a plurality of circumfer-

entially spaced apertures, is rigidly secured to the bottom of box 5 at the center thereof, and has the threaded depending socket 7^a in which is secured the upper threaded end 60 of an elongated vertical spindle 8 having on its intermediate portion an outwardly projecting lug 8^a. The upper threaded end 65 of spindle 8 is also provided with a lock nut 9 adapted to engage the lower end of socket 65 plate 7 to lock spindle 8 thereto. An elongated tubular member 10, having its upper end 10^a cut at an oblique angle to the axis thereof, is vertically seated in the top of post 6. Spindle 8 is telescoped within the tubular 70 member 10 and supported therein by means of the engagement of lug 8^a with the upper or outer inclined end. Obviously, when the box 5 is struck or swung to one side, the inclined or oblique end of the tubular member 10 will automatically cause the box to be returned or swung back to normal position with the door of the box in proper outward position to receive the mail from the carrier. The pitch of the upper end 10^a of 80 tubular member 10 is sufficient to readily return the box to normal position and to permit the same to be readily swung if struck by the vehicle of the mail carrier, or passing domestic animals.

The spindle 8 is loosely mounted in the tubular member 10 and may be readily lifted therefrom and the box removed from the post, if, for any reason, desired.

From the above description, it will be apparent that a simple but highly efficient mounting for mail boxes and other receptacles has been invented, comprising few parts and capable of being manufactured at exceedingly low cost. The device may be easily installed on a standard box and supporting post.

Extensive actual usage of the device has shown it to be highly efficient for the purposes intended.

It will, of course, be understood that various changes can be made in the form, details, and arrangement of parts without departing from the scope of the invention, which, generally stated, consists in a device capable of carrying out the objects above enumerated and such as shown and described and set forth in the appended claims.

What is claimed is:

1. The combination with a support, of a 110 mounting for a mail box or other receptacle, comprising an upright tubular member se-

cured to said support and having its upper end cut at an oblique angle to its axis, a threaded socket secured to the underside of said mail box or other receptacle, and a vertical spindle having threaded engagement with said socket at its upper end and having its lower portion disposed within said tubular member and carrying at one side a pro-

jecting lug engaging the upper end of said tubular member.

10

2. The structure set forth in claim 1, and a lock nut on the upper end of said spindle adapted to engage against the lower end of said socket.

In testimony whereof I affix my signature.
OLE M. AARSETH.
